ICE TRAY

Francis P. Keiper, Philadelphia, Pa., assignor to
 General Motors Corporation, Dayton, Ohio, a
 corporation of Delaware

Application June 8, 1938, Serial No. 212,487
 Renewed February 5, 1940

15 Claims. (Cl. 62—108.5)

This invention relates to liquid freezing devices and particularly to ice trays and grids therefor employed in household refrigerators.

One of the objects of my invention is to provide 5 an improved rigid movable wall grid structure adapted to be removably disposed in an ice tray for dividing the tray into four or more longitudinal rows of ice block compartments and a novel method of removing the grid from the tray 10 and ice blocks from the grid structure without applying heat thereto.

Another object of my invention is to provide 15 an improved unitary rigid metal wall grid structure comprising a plurality of spaced apart longitudinal walls and a plurality of spaced apart transverse walls for dividing a tray into four or more longitudinal rows of ice block compartments and wherein one of the longitudinal walls is movable in one direction relative to other 20 longitudinal walls thereof to cause movement of these other longitudinal walls in another direction relative to said one longitudinal wall to break ice blocks loose from the grid structure.

In carrying out the preceding object it is an- 25 other object of my invention to simultaneously move a plurality of transverse walls of the grid structure relative to the longitudinal grid wall to enlarge the ice block compartments and liberate ice blocks therefrom.

30 A further object of my invention is to provide an improved unitary rigid wall grid structure comprising a plurality of spaced apart longitudinal walls and a plurality of spaced apart normally angularly disposed transverse walls divid- 35 ing a tray into four or more longitudinal rows of ice block compartments and wherein movement of one of the longitudinal walls lengthwise of other longitudinal walls thereof causes these other longitudinal walls to tilt in a direction 40 transversely of the structure and causes the angularly disposed transverse walls to tilt into a substantially vertical position simultaneously with tilting of the longitudinal walls to break ice blocks from the grid walls and to enlarge the ice 45 block compartments to liberate the loosened ice blocks from the grid structure.

A still further object of my invention is to pro- 50 vide a unitary grid structure with leverage mechanism including a pair of levers pivotally mounted thereon and rotatable relative thereto for applying force to a tray to elevate the grid structure together with ice bonded thereto relative to the tray and which levers are movable relative to one another to cause movement of the grid walls as 55 specified in the foregoing objects.

Still further and more specific objects and advantages reside in the operation of my improved grid structure and in novel combinations and arrangement of parts thereof to provide a durable structure as will more fully appear in the 5 course of the following description.

In the drawings:

Fig. 1 is a top plan view of an improved freezing device having a grid structure constructed according to my invention disposed in the tray 10 thereof;

Fig. 2 is a longitudinal vertical sectional view of the tray of the improved freezing device taken on the line 2—2 of Fig. 1 and showing the grid thereof partly in elevation and partly in section; 15

Fig. 3 is a transverse vertical sectional view of the device taken on the line 3—3 of Fig. 1;

Fig. 4 is a transverse vertical sectional view through the freezing device taken on the line 4—4 of Fig. 1; 20

Fig. 5 is an enlarged fragmentary sectional view taken on the line 5—5 of Fig. 1 showing the attachment of a lever to the grid of the device;

Fig. 6 is a view similar to Fig. 2 showing the grid structure and ice blocks bonded thereto ele- 25 vated relative to the tray;

Fig. 7 is a top plan view of the grid removed from the tray and disclosing walls thereof moved to release ice blocks from the grid;

Fig. 8 is a side view of the grid structure as disclosed in Fig. 7; and 30

Fig. 9 is a vertical transverse sectional view of the grid structure with the walls thereof moved as shown in Fig. 7 and taken on the line 9—9 thereof. 35

Referring to the drawings, for illustrating the invention, I have disclosed my improved liquid freezing device as including a metal ice tray 10 having a metallic grid structure removably disposed therein. The tray 10 has side walls 11, a bottom wall 12 and opposed end walls 13 and 14. The tray side walls 11 and the front wall 13 thereof may diverge outwardly toward the top of the tray. The tray back wall 14 is diverged outwardly toward the top of the tray a greater distance than other walls thereof for the purpose of facilitating removal of the grid from the tray as will become apparent hereinafter. The upright walls 11, 13 and 14 of tray 10 have their upper portion rolled over as at 15 to provide a rim 40 which extends continuously around the top of the tray to increase its structural strength. A portion of the metal of tray 10 is extended downwardly from the rim 15, as at 16 (see Fig. 2) at the front of the tray and provides a mounting or 45

support for a heavy metal piece 17 which has a handle 18 pivotally secured thereto, as at 19. The handle 18 is provided with a cam surface or surfaces 20 adapted to engage the support on a freezing shelf of an evaporator of a refrigerating system to facilitate removal of the freezing device from the evaporator as will hereinafter be more fully described.

The tray 10 of the freezing device has a unitary metallic grid structure generally represented by the reference character 21 removably disposed therein. The grid 21 includes three single-thickness substantially non-flexible horizontally spaced apart and parallel longitudinal metal partitioning walls 22, 23 and 24 and a plurality of single-thickness substantially non-flexible metal partitioning walls 26 extending transversely of and in spaced apart relation along the longitudinal walls 22, 23 and 24 to divide the interior 10 of tray 10 into four longitudinal rows of open top cells or compartments 27. The central longitudinal wall 23 is provided with a plurality of equally spaced apart slots 28 (see Fig. 2) extending upwardly from the bottom edge thereof. 15 These slots 28 are formed by the angled walls 29 and 30 and are greater in width at their lower ends. Each of the side longitudinal walls 22 and 24 is provided with a plurality of equally spaced apart slots 31 (see Fig. 2) extending 20 downwardly from the top edge thereof. These slots 31 are formed by the angled walls 32 and 33 and are of greater width at their upper ends. Each of the spaced apart transverse walls 26 have a pair of slots 34 extending upwardly from the bottom edge thereof and formed by the angled walls 35, 36 and 37 (see Fig. 5). These slots 34 are of greater width at their lower ends than at their upper closed ends. Each transverse wall 26 also has a straight walled slot 38 25 located between the spaced apart slots 34 therein and extending downwardly from the top edge of wall 26. It will be noted that slots 28 in longitudinal wall 23 receive the web portion 41 of transverse walls 26 located below the slots 38 30 therein and slots 31 in the two other or side longitudinal walls 22 and 24 receive the web portion 42 of transverse walls 26 located above the slots 34 therein. In order to prevent vertical movement of the longitudinal walls 22, 23 and 24 35 relative to one another and to lock the transverse walls 26 thereon, I extend a rod 45 through ears 46 provided at the one end of the walls 22, 23 and 24. The rod 45 is round and extends through round holes provided in the ears 46 of longitudinal walls 22 and 24. The rod 45 also extends 40 through a horizontally elongated opening 47 (see Fig. 2) provided in the ear 46 on the central longitudinal wall 23 for a purpose to become apparent hereinafter. The rod 45 is provided with 45 enlarged ends 48 to prevent its removal from walls 22, 23 and 24 and to lock the walls of the grid structure together at the one end thereof.

The parts at the other end of the grid structure 21 are locked together by a leverage mechanism (see Fig. 1), the operation of which will be described in detail in the description of operation of the device. This leverage mechanism includes a pair of levers 51 located beside one another and comprising a handle end 52 and a 55 short bent end portion 53 which lies over the rim 15 of tray 10. Each lever 51 has an integral part 54 extending from a side thereof through a rounded opening provided in an ear portion 55 of the longitudinal walls 22 and 24, which part 75 is beaded over as at 56. The fit of part 54 within

the opening provided in the walls 22 and 24 is loose to permit angular movement of part 54 within the opening and relative to walls 22 and 24 as will become apparent hereinafter. The other side of each lever 51 is provided with an 5 ear 57, and the two levers are connected together through a link 58 pivotally secured to the ears 57. Link 58 is a rounded member and extends through a round hole 59 formed in an upstanding ear 61 provided on the central longitudinal grid 10 wall 23 (see Figs. 4 and 5). The link 58 is hollowed out inwardly from each end thereof to receive the ear portions 57 of levers 51, and a rivet or the like 62 passing through the link 58 and ears 61 secures the levers together. The 15 levers 51 normally lie parallel to one another with the handle end 52 of one lever disposed in a horizontal plane slightly above the handle end 52 of the other lever (see Fig. 2). It will be noted that the levers 51 are pivotally mounted to 20 the grid structure 21 for rotation in a direction upwardly of the structure and that the handle ends 52 of levers 51 can be moved in a horizontal direction toward one another.

The longitudinal grid walls 22 and 24 have a 25 plurality of spaced apart portions 65 extending upwardly from their top edges and bent at an angle relative thereto to provide cam feet 66 (see Figs. 1 and 3). The central longitudinal partitioning grid wall 23 is provided with integral 30 horizontally projecting portions 67 extending from the top edge thereof. Each of these projecting portions 67 terminates in an upwardly directed reversely bent end 68 and provides a cam shoe which fits over the cam feet 66 on walls 35 22 and 24. The rigid metal longitudinal grid walls 22, 23 and 24 are normally disposed in a vertical position, and the rigid metal transverse grid walls 26 are normally angularly disposed or are inclined with respect to the bottom of tray 40 10 as shown in Fig. 1 of the drawings. The normal inclination of the grid walls 26 provides the four longitudinal rows of ice block compartments 27 with a parallelogram form in horizontal cross section. It will be noted that the slots 45 34 in transverse grid walls 26 permit tilting of the longitudinal grid walls 22 and 24 in a transverse direction relative to the grid structure and that slots 28 in the central longitudinal grid wall 23 and slots 31 in the other two or side longitudinal walls 22 and 24 permit tilting of the transverse grid walls 26 in a direction longitudinally of the grid structure 21. While the grid structure 21 is of a unitary construction and is removably disposed in tray 10, the rigid metal walls 55 thereof are movably connected together, as stated, and are movable relative to one another in a manner and for a purpose to be hereinafter more fully described.

Assume that water has been frozen in the 60 freezing device disclosed in the form of ice blocks 70 in compartments 27, by the cooling effect produced by an evaporator of a refrigerating system, and the device is to be removed from its support in or on the evaporator to permit 65 harvesting of the ice blocks 70. Handle 18 is clasped by the hand and pulled forward, thereby rotating about its pivotal mountings 19 to cause the cam surface 20 thereon to apply force between the freezing device and its support. This 70 force elevates the freezing device relative to its support and breaks the ice bond therebetween to permit the device to be readily removed from the evaporator. The freezing device is, after removal thereof from the evaporator, placed on a

table top or ledge and the handle ends 52 of levers 51 are simultaneously elevated about their pivotal mounting relative to the grid 21. Elevation of the handle ends 52 of levers 51 causes the short bent end 53 of the levers to engage and apply force to the rim 15 of tray 10. This force applied to tray 10 causes the grid structure 21 and ice blocks 70 adhering thereto to be broken loose from and elevated relative to the tray. This raising movement of levers 51 is illustrated in Fig. 6 of the drawings, and it will be noted that portions 54 of levers 51 have rotated within the openings provided therefor in the grid walls 22 and 24 and that the round link 58 has also rotated within its opening 59 provided in the portion 61 of the central longitudinal wall 23. After the bond between the ice blocks and tray 10 has been broken, by elevation of the unitary metallic grid structure 21 together with the ice blocks 70 adhering thereto relative to the tray, the grid structure 21 and ice blocks 70 may be readily removed from the tray or raised above same. Thereafter, the levers 51 are moved back toward the grid structure so as to be substantially in or near horizontal alignment therewith; and the handle ends 52 of the levers are then squeezed or moved toward one another. This position of the levers 51 is illustrated in Figs. 7, 8 and 9 of the drawings, and it will be noted that the scissor-like movement of the handle ends 52 of levers 51 has caused the levers to pivot about their pivotal mounting rivets 62. Since the levers 51 are prevented from moving lengthwise relative to the longitudinal grid walls 22 and 24 by the portions 54 thereof being secured to these walls, the pivoting of the levers about rivets 62 causes the link 58 and, consequently, the central longitudinal partitioning grid wall 23 to move lengthwise of the grid structure 21 relative to the longitudinal walls 22 and 24. Movement of the central wall 23 relative to and lengthwise of longitudinal walls 22 and 24 moves the cam shoes 68, formed integral with wall 23, toward the lever end of the structure and these cam shoes 68 ride upon or over the cam feet 66 and, due to the angled disposition of these camming parts, a pulling force is applied to the upper portions of the longitudinal grid walls 22 and 24. This pulling force applied to walls 22 and 24 causes these longitudinal grid walls to tilt and slide in a direction transversely of the grid structure and out of their normal vertical disposition into the angled position shown in Figs. 7, 8 and 9. This movement of the longitudinal grid walls 22 and 24 relative to the central longitudinal wall 23 breaks the ice blocks 70 loose therefrom and moves the blocks of the outer longitudinal rows thereof outwardly at a side of the structure 21. Movement of the central wall 23 relative to and lengthwise of the longitudinal walls 22 and 24 also causes the walls 30 of slots 28 to engage the transverse grid walls 26 and simultaneously move or tilt these transverse walls from their normal angled or inclined disposition into a substantially vertical position. The transverse walls 26 in moving in a direction longitudinally of the grid structure from their normal angled disposition into a vertical position hinge about the top of slots 28 in wall 23 and about the bottom of slots 31 in walls 22 and 24. Movement of the transverse grid walls 26 as described breaks the ice blocks 70 loose therefrom and changes the horizontal cross sectional contour of the ice compartments 27 from a parallelogram shape into a rectangular or

square shape (see Fig. 8). This change of the horizontal cross sectional contour of compartments 27 slightly increases the distance between the transverse walls 26 and thereby enlarges the compartments 27 in a direction along the length 5 of the grid structure 21. The ice blocks 70 around the peripheries of the grid structure 21 are simultaneously moved in two different directions by the simultaneous tilting of walls 22 and 24 transversely of the grid and tilting of walls 26 in a direction lengthwise of the grid. The breaking of longitudinal grid walls 22 and 24 away from the ice blocks in the two central rows of the four longitudinal rows thereof facilitates breaking of the ice blocks in these two central 15 rows thereof from the longitudinal grid wall 23 by movement of the transverse grid walls 26. Since the ice compartments are slightly enlarged simultaneously with the breaking of the ice bond between the grid walls 22, 23, 24 and 26 the 20 loosened ice blocks 70 freely fall out of their compartments 27 and away from the grid structure 21. The change in the position of the grid walls to effect liberation of the ice blocks 70 from compartments 27 is illustrated by showing 25 the blocks 70 within the compartments 27 in Figs. 7, 8 and 9. It is to be understood, however, that these figures in the drawings are merely for illustrative purposes and that, when the grid walls 22, 23, 24 and 26 are moved as described 30 and as shown, the ice blocks 70 will be liberated from the structure 21. Movement of rigid walls of the grid as described and enlargement of the ice compartments does not alter the unitary character of the structure 21; and, upon returning 35 the levers 51 to their normal position shown in Figs. 1 and 2 of the drawings, grid walls 22, 23, 24 and 26 will be moved back into their normal ice block forming position and the grid structure can be repositioned in a tray. Release of ice blocks from their compartments may be facilitated, if desired, by treating or coating walls of the compartments with a waxy or the like water-repellent substance which will substantially reduce the adherence of the water or 40 bondage of ice to walls of the grid structure. It will be seen from the foregoing that I have provided an improved freezing device by providing an ice tray grid structure which divides the tray into four or more longitudinal rows of 45 ice blocks and by providing an effective method of removing all ice blocks from the structure without application of heat thereto. By providing movement of a central longitudinal grid wall lengthwise of longitudinal walls disposed on each 50 side thereof to effect movement or tilting of these side longitudinal walls in another or different direction while at the same time moving or tilting transverse walls of a grid structure, adapted to form four or more longitudinal rows 55 of ice blocks in a tray, I am enabled to increase the ice block capacity or the number of ice blocks to be formed in a freezing device. I, therefore, reduce the number of such freezing 60 devices ordinarily required in a household refrigerating apparatus or provide a device for use in a small refrigerator which is capable of producing a greater number of ice blocks. My improved device is strong and durable and effective 65 in response to a minimum of manual force applied thereto to remove ice blocks without unduly shattering the blocks. By constructing the grid structure entirely of rigid metal parts, I eliminate distortion of parts thereof and also 70 75

retain the fast freezing characteristics of metal tray and grid combinations.

While the form of embodiment of the invention as herein disclosed, constitutes a preferred form, it is to be understood that other forms might be adopted, all coming within the scope of the claims which follow.

What is claimed is as follows:

1. In combination, a tray having a grid disposed therein, said grid comprising a plurality of horizontally spaced apart longitudinal walls and a plurality of walls extending transversely thereto in spaced apart relation along the length thereof, said walls being secured together to 10 form a unitary removable grid structure dividing the interior of the tray into a plurality of longitudinal rows of ice block compartments, one of the longitudinal walls of said grid structure being movable lengthwise of another longitudinal 15 wall thereof to cause said another longitudinal wall to tilt in a direction transverse of said grid structure, means for elevating said unitary grid structure together with ice blocks adhering thereto relative to the tray, and means for moving 20 said grid walls relative to one another after said unitary structure has been elevated relative to the tray for breaking the bond between the compartment walls and ice blocks therein.

2. In combination, a tray having a grid disposed therein, said grid comprising a plurality of horizontally spaced apart longitudinal walls and a plurality of walls extending transversely thereto in spaced apart relation along the length thereof, said walls being secured together to form 30 a unitary removable grid structure dividing the interior of the tray into a plurality of longitudinal rows of ice block compartments, one of the longitudinal walls of said grid structure being movable lengthwise of another longitudinal wall 35 thereof to cause said another longitudinal wall to tilt in a direction transverse of said grid structure, said movement of said one longitudinal grid wall lengthwise of said another longitudinal grid wall also causing the transverse grid walls to 40 tilt in a direction longitudinally of said grid structure, means for elevating said unitary structure together with ice blocks adhering thereto relative to the tray, and means for moving 45 said grid walls relative to one another after said unitary structure has been elevated relative to the tray for breaking the bond between the compartment walls and ice blocks therein.

3. In combination, a tray having a grid disposed therein, said grid comprising a plurality of horizontally spaced apart longitudinal walls and a plurality of walls extending transversely thereto in spaced apart relation along the length thereof, said walls being secured together to 55 form a unitary removable grid structure dividing the interior of the tray into four or more longitudinal rows of ice block compartments, said longitudinal grid walls being normally vertically disposed and said transverse grid walls normally being inclined with respect to the bottom of the tray to provide said compartments with a parallelogram form in at least one direction of cross section therethrough, one of the longitudinal walls of said grid structure being movable relative to another longitudinal wall 60 thereof to cause movement of said another longitudinal wall out of its normal vertical position, said movement of said one longitudinal grid wall relative to said another longitudinal grid wall also causing the transverse grid walls to be 65 simultaneously tilted out of their normal in-

clined position to enlarge said ice block compartments, means for elevating said unitary grid structure together with ice blocks adhering thereto relative to the tray, and means for moving said grid walls relative to one another after said unitary structure has been elevated relative to the tray for breaking the bond between the compartment walls and ice blocks therein.

4. In combination, a tray having a grid disposed therein, said grid comprising a plurality of horizontally spaced apart longitudinal walls and a plurality of walls extending transversely thereto in spaced apart relation along the length thereof, said walls being secured together to form a unitary removable grid structure dividing the interior of the tray into four or more longitudinal rows of ice block compartments, said longitudinal grid walls being normally vertically disposed and said transverse grid walls normally being inclined with respect to the bottom of the tray to provide said compartments with a parallelogram form in at least one direction of cross section therethrough, one of the longitudinal walls of said grid structure being movable lengthwise of another longitudinal wall 20 thereof to cause said another longitudinal wall to tilt in a direction transverse of said grid structure out of its normal vertical position, said movement of said one longitudinal grid wall lengthwise of said another longitudinal grid wall 30 also causing the transverse grid walls to be simultaneously tilted in a direction longitudinally of said grid structure out of their normal inclined position to enlarge said ice block compartments, means for elevating said unitary grid structure together with ice blocks adhering thereto relative to the tray, and means for moving said grid walls relative to one another after said unitary structure has been elevated relative to the tray for breaking the bond between the 35 compartment walls and ice blocks therein.

5. In combination, a tray having a grid disposed therein, said grid comprising a central longitudinal wall and a longitudinal wall spaced from and disposed on each side of said central longitudinal wall, said grid also comprising a plurality of walls extending transversely to said longitudinal walls in spaced apart relation along the length thereof, said walls being secured together to form a unitary removable grid structure dividing the interior of the tray into four or more longitudinal rows of ice block compartments, said longitudinal grid walls being normally vertically disposed and said transverse grid walls normally being inclined with respect to the bottom of the tray to provide said compartments with a parallelogram form in at least one direction of cross section therethrough, said central longitudinal wall of said grid structure having a connection with the longitudinal walls at each 50 side thereof and being movable lengthwise of said side longitudinal walls, said central longitudinal wall of said grid structure also having a connection with said transverse walls thereof, a pair of levers pivotally mounted upon the grid structure 55 and operable to apply force to the tray for elevating the unitary grid structure together with ice blocks adhering thereto relative to the tray, said levers also being pivotally mounted for movement relatives to one another for moving said central 60 longitudinal grid wall lengthwise of said side longitudinal grid walls after said unitary structure has been elevated relative to the tray, and said connections between said central longitudinal grid wall and said side longitudinal grid walls 65 70

and said transverse grid walls being constructed and arranged whereby the lengthwise movement of said central longitudinal grid wall causes tilting of said side longitudinal walls transversely of 5 said grid structure and tilting of said transverse walls longitudinally of the grid structure for breaking the bond between the compartment walls and ice blocks therein.

6. A grid for disposition in an ice tray and removable therefrom as a unit comprising, a plurality of substantially non-flexible horizontally spaced apart longitudinal partitions and a plurality of substantially non-flexible partitions extending transversely through the plane of said 10 longitudinal partitions in spaced apart relation along the length thereof, said partitions being movably connected together to provide a unitary structure and forming walls of a plurality of longitudinal rows of ice block compartments, 15 leverage mechanism carried by said unitary structure and operable for moving one of said longitudinal partitioning walls lengthwise of another longitudinal partitioning wall thereof, and said connection between the partitioning walls of 20 said grid structure being such that the lengthwise movement of said one longitudinal partitioning wall causes tilting of said another longitudinal partitioning wall transversely of the structure and tilting of said transverse partitioning walls longitudinally of the structure to break the bond between 25 ice blocks and their compartment walls.

7. A grid for disposition in an ice tray and removable therefrom as a unit comprising, a central substantially non-flexible longitudinal partition and a substantially non-flexible longitudinal partition located on each side of said central longitudinal partition and spaced horizontally therefrom, said grid also comprising a plurality of substantially non-flexible partitions extending 30 through the plane of said longitudinal partitions in spaced apart relation along the length thereof, said partitions being movably connected together to provide a unitary grid structure and forming walls of four or more longitudinal rows of ice 35 block compartments, leverage mechanism carried by said unitary grid structure and operable for moving said central longitudinal partitioning wall in one direction relative to said side longitudinal partitioning walls, and said connection between the partitioning walls of said grid structure being constructed and arranged so that the movement of said central longitudinal partitioning wall causes said side longitudinal partitioning walls to move in another direction relative to said central longitudinal partitioning wall and also causes 40 said transverse partitioning walls to move relative to said longitudinal partitioning walls to break the bond between ice blocks and their compartment walls.

8. A grid for disposition in an ice tray and removable therefrom as a unit comprising, a central substantially non-flexible longitudinal partition and a substantially non-flexible longitudinal partition located on each side of said central longitudinal partition and spaced horizontally therefrom, said grid also comprising a plurality of substantially non-flexible partitions extending through the plane of said longitudinal partitions in spaced apart relation along the length thereof, 45 said partitions being movably connected together to provide a unitary grid structure and forming walls of four or more longitudinal rows of ice block compartments, said longitudinal partitioning walls being normally vertically disposed and 50 said transverse partitioning walls normally being

disposed at an angle relative to the vertical to provide said compartments with a parallelogram form in at least one direction of cross section therethrough, leverage mechanism carried by 5 said unitary grid structure and operable for moving said central longitudinal partitioning wall lengthwise of said side longitudinal partitioning walls, and said connection between the partitioning walls of said grid structure being constructed and arranged so that the lengthwise movement 10 of said central longitudinal partitioning wall causes tilting of said side longitudinal partitioning walls transversely of the structure and simultaneous tilting of said transverse partitioning walls out of their normal angled disposition in a 15 substantially vertical position to break the bond between ice blocks and their compartment walls.

9. A grid for disposition in an ice tray comprising, a plurality of horizontally spaced apart longitudinal walls and a plurality of walls extending transversely thereto in spaced apart relation along the length thereof, said walls being connected together to provide a removable unitary structure and forming a plurality of longitudinal rows of ice block compartments, one of 20 said longitudinal walls of the grid structure being movable in one direction relative to another of said longitudinal walls thereof, and the connection between the walls of said grid structure being so constructed and arranged that said 25 movement of said one longitudinal wall causes movement of said another longitudinal wall in a direction substantially at right angles to the direction of movement of said one longitudinal wall to break the bond between ice blocks and 30 their compartment walls.

10. A grid for disposition in an ice tray comprising, a plurality of horizontally spaced apart longitudinal walls and a plurality of walls extending transversely thereto in spaced apart relation along the length thereof, said walls being connected together to provide a removable unitary structure and forming a plurality of longitudinal rows of ice block compartments, one of 40 said longitudinal walls of the grid structure being movable in one direction relative to another of said longitudinal walls thereof, said transverse walls also being movable relative to said longitudinal walls, and the connection between the walls of said grid structure being so constructed and arranged so that said movement of said one longitudinal wall causes movement of said another longitudinal wall in a direction substantially at 45 right angles to the direction of movement of said one longitudinal wall and movement of said transverse walls to break the bond between ice blocks and 50 their compartment walls.

11. A grid for disposition in an ice tray comprising, a central longitudinal wall and a longitudinal wall spaced from and disposed on each side of said central longitudinal wall, a plurality of walls extending transversely to said longitudinal walls in spaced apart relation along the length thereof, said walls being connected together to provide a removable unitary structure and forming four or more longitudinal rows of ice block compartments, one of said longitudinal walls of the grid structure being movable in one direction relative to the other two longitudinal walls thereof, and the connection between the walls of said 60 grid structure being so constructed and arranged that said movement of said one longitudinal wall causes movement of said other two longitudinal walls in another direction of movement relative to the direction of movement of said one longitudinal wall.

tudinal wall to break the bond between ice blocks and their compartment walls.

12. A grid for disposition in an ice tray comprising, a central longitudinal wall and a longitudinal wall spaced from and disposed on each side of said central longitudinal wall, a plurality of walls extending transversely to said longitudinal walls in spaced apart relation along the length thereof, said walls being connected together to provide a removable unitary structure and forming four or more longitudinal rows of ice block compartments, one of said longitudinal walls of the grid structure being movable in one direction relative to the other two longitudinal walls thereof, said transverse walls also being movable relative to said longitudinal walls, and the connection between the walls of said grid structure being so constructed and arranged that said movement of said one longitudinal wall causes movement of said other two longitudinal walls in another direction of movement relative to the direction of movement of said one longitudinal wall and movement of said transverse walls to break the bond between ice blocks and their compartment walls.
13. A grid for disposition in an ice tray comprising, a central longitudinal wall and a longitudinal wall spaced from and disposed on each side of said central longitudinal wall, a plurality of walls extending transversely to said longitudinal walls in spaced apart relation along the length thereof, said walls being connected together to provide a removable unitary structure and forming four or more longitudinal rows of ice block compartments, certain of said walls of the grid structure being movable in one direction relative to other walls thereof, and the connection between the walls of said grid structure being so constructed and arranged that said movement of said certain walls causes movement of said other walls thereof in another direction of movement

relative to said one direction of movement of said certain walls to break the bond between ice blocks and their compartment walls.

14. A grid for disposition in an ice tray comprising, a plurality of horizontally spaced apart longitudinal walls and a plurality of walls extending transversely thereto in spaced apart relation along the length thereof to form a row of ice block compartments on each side of said plurality of longitudinal walls, said walls being connected together to provide a removable unitary grid structure, one of said longitudinal walls of the grid structure being movable lengthwise relative to another of said longitudinal walls, means for causing said relative lengthwise movement of said one longitudinal wall, and the connection between the walls of said grid structure being so constructed and arranged that said lengthwise movement of said one longitudinal wall causes movement of said transverse walls relative to said longitudinal walls to break the bond between ice blocks and their compartment walls.

15. A unitary removable grid structure for disposition in a freezing tray comprising, a plurality of horizontally spaced apart substantially non-flexible partitions movably connected together to provide walls of an ice block compartment therebetween, means for imparting force directly to one of said partitions to move same relative to another of said partitions, means for transmitting the force imparted to said one partition to said another partition, and said last named means being so constructed and arranged that movement of said one partition causes movement of said another partition laterally with respect to the direction of movement of said one partition to break a bond between an ice block and its compartment walls.
